(57) **CLAIM**

The ornamental design for a tyre inflator/deflator, as shown and described.

DESCRIPTION

FIG. 1 is a perspective view of a tyre inflator/deflator of the present invention;

FIG. 2 is a front view thereof;

FIG. 3 is a rear view thereof;

FIG. 4 is a top plan view thereof;

FIG. 5 is a bottom plan view thereof;

FIG. 6 is a right side view thereof; and,

FIG. 7 is a left side view thereof.

The broken lines in FIGS. 3 and 5 are included for the purpose of illustrating portions of the tyre inflator/deflator that form no part of the claimed design.
